UNITED STATES PATENT OFFICE.

JOHN NICHOLS AND EDMUND D. BROWN, OF BATTLE CREEK, MICHIGAN;
SAID BROWN ASSIGNOR TO SAID NICHOLS.

IMPROVEMENT IN HORSE-POWERS.

Specification forming part of Letters Patent No. 136,754, dated March 11, 1873.

To all whom it may concern:

Be it known that we, JOHN NICHOLS and EDMUND D. BROWN, of Battle Creek, county of Calhoun, and State of Michigan, have invented a new and useful Improvement in Horse-Power, of which the following is a full, clear, and exact description, reference being had to the accompanying drawing making part of this specification, in which—

Figure 1 is a plan or top view of a triple-gear horse-power. Fig. 2 is a similar view with the top rim and gearing removed, showing the the bed-plate. Fig. 3 is a sectional view through line *x x*, Fig. 1; and Fig. 4 is a section through line *y y*, Fig. 1.

Similar letters of reference denote corresponding parts in all the figures.

In the manufacture of horse-powers known as the "triple-gear," serious difficulty has been found in casting the parts so that, when the machine was put together for use or in furnishing repairs, the master-pinions would perfectly mesh with the central pinion and master-wheel, for the reasons, viz: First, the castings being so large it has been found difficult if not impossible to get them of even size, the difference in "shrinkage" making a wide variation. Second, such a casting will warp or spring in cooling, and even if the holes for the shafts are "bored" out true with each other, yet in bolting the casting to the frame timbers it will be sprung more or less, causing the shafts to stand out of line with each other—*i. e.*, not "plumb"—and in consequence the gears will not mesh into each other with exactness; this is particularly true of the three spur-wheels which mesh into the central pinion, a slight variation from plumb causing them to mesh into the central pinion on a "twist." Third, the variation in size of the bed-rim renders it difficult to get spur-wheels that will exactly fit into proper mesh with the central pinion, and more especially is it difficult to get the master-wheel to fit, as that too will vary considerably in size. Fourth, the master-wheel and master-wheel pinions wear faster, and the master-wheel soon gets "loose" in mesh, which cannot be remedied in the old construction, and this necessitates the substitution of a new one, which is expensive; and even then the master-

wheel may not fit on account of shrinkage, though it was cast from the same pattern as the original.

The object of this invention is to remedy the above-named defects, and consists in providing adjustable bearings for the spur-wheel shafts so that the mesh of the gears can be regulated at will, as will be described.

In the drawing, *A* represents a bed-plate and *A'* the top plate or rim, these plates or rims being cast in the usual manner, except that the holes for the spur-wheel shafts are elongated in lines radiating from the center shaft, forming radial slots to permit the adjustment of said shafts. The socket for the central shaft is cast with the bed-rim as usual, or may be cast separately and bolted to the bed-rim. *B B* are bearings or socket-plates for the spur-wheel shaft *C*, cast separate from the bed-plate and top rim, and bored out to exactly fit the ends of said shafts *C* stepped therein. The socket-plates *B* are secured to the bed-rim *A* by bolts *b b*, the bolt-holes in said socket-plates being elongated or slotted in the same manner that the bed-rim is for shafts *C*, and in lines parallel with the slot in said rim. The upper socket-plates *B'* for the shafts *C* extend outward beyond the rim *A'* and over lips *d* formed on said rim, and are provided each with a lip or flange, which projects downward outside of the rim, as shown at *b'*, Fig. 3. *b'* is a set-screw working in the flange *b'*, and bearing against the bed-rim for adjusting the socket-plates *B'* and with it the upper end of shaft *C*, having its bearing therein. *d' d'* are ribs formed upon the bed-plate and top rim, between which the socket-plates are placed, said ribs serving to assist the bolts in preventing any lateral movement or displacement of the shafts, and limiting the adjustment of said socket-plates and shafts, except in and out or in radial line. The shafts *C*, which are stationary, are further secured and made to assist in holding the socket-plates firmly in place by means of nuts *C' C'*. The manner of effecting the desired adjustments of the shafts *C* and their spur-wheels *C'* to cause the latter to mesh perfectly with the master-wheel and central pinion will be readily understood without further description. By the adjustment of one or both ends of the spur-

wheel shafts C, said shafts may be readily "trued up" to overcome any difficulty arising from warping or uneven shrinking of bed-plate and top-rim castings, or to accommodate the varying sizes of the master-wheel or spur-wheels arising from the same cause, viz., variation in shrinkage and also from wear, and thereby the machine is adapted to receive new parts in place of such as may have become worn out or broken.

Having thus described the invention, what is claimed as new is—

1. The bed-plate and top rim, (either or both,) provided with adjustable bearings or socket-plates for the spur-wheel shafts, substantially as and for the purpose set forth.

2. The adjustable bearing or socket-plates for the spur-wheel shafts, in combination with slots in the rim and top plates, (either or both,) for permitting the adjustment of the spur-

wheel shafts in radial lines, substantially as and for the purpose set forth.

3. The socket-plate B, provided with slotted bolt-holes in combination with the slotted bed-plate and bolts b, for adjusting the lower ends of the spur-wheel shafts, as described.

4. The flanged socket-pieces B' and set-screws b², for adjusting the upper ends of shafts C, as described.

5. The bed-rim and top plate A A', provided with the ribs d d, in combination with the adjustable socket-plates, substantially as described.

In testimony whereof we have hereunto set our hands this 31st day of January, A. D. 1873.

JOHN NICHOLS.

E. D. BROWN.
